UNITED STATES PATENT OFFICE.

CHARLES S. SHIVLER, OF BROOKLYN, NEW YORK.

ELECTRICAL SWITCH.

SPECIFICATION forming part of Letters Patent No. 295,445, dated March 18, 1884.

Application filed August 29, 1883. (No model.)

To all whom it may concern:

Be it known that I, CHARLES S. SHIVLER, of Brooklyn, Kings county, New York, have invented certain new and useful Improvements 5 in Electrical Switches, of which the following is a specification.

My invention aims to provide a permutation or combination switch for burglar-alarm or similar circuits, whereby the owner or other 10 entrusted person, by first setting the switch to a certain known combination or position, may thus previously open or close the general circuit, as the case may be, and then open a door or window without sounding the alarm, thus 15 producing the effect of a combination-lock in the circuit, which will enable any of the protected parts to be opened silently by a person knowing the combination, but not otherwise. Where the switch is applied to an open circuit, it will of course act to keep the circuit open when turned to that proper combination, whereas when applied to a closed circuit it 20 will act to keep the circuit closed when turned to the combination for which it is set, as will be understood.

My invention may therefore be briefly stated to consist in one or more rotary or sliding commutators or switches movable over a graduated range or circle, at one point of which 30 the circuit is made or broken, with means for indicating to the entrusted person the position or graduation of said point, and means for changing the numbers, graduations, or indications representing said position, whereby the 35 person having control of said switch may set it to any desired combination or number, and will be enabled to readily close or break the circuit by turning the switch to said number or graduation, whereas those not knowing this 40 graduation or combination cannot do so without having to try an infinite number of changes, which will deter all such attempts. In practice, I prefer to use a series of two or more of such switches, the circuit being completed 45 from one to the other, so that both switches must be set to the proper combination before the circuit will be closed or opened, thereby complicating the changes and making it more difficult for the circuit to be opened by any 50 one not in its secret.

My invention also consists in certain special

details of construction in addition to the main features above described, as hereinafter fully set forth.

Figure 1 of the annexed drawings is a front 55 elevation of my novel permutation-switch or commutator adapted for an open circuit, and Fig. 2 is a cross-section thereof on line *xx*. Fig. 3 is a rear elevation of the switch shown in Fig. 1, showing the circuit-connections in 60 diagram. Fig. 4 is a similar rear view of a switch adapted for closed circuits, with the circuits shown in diagram.

Referring to the drawings, I will first describe the form of my invention which is 65 adapted for open circuits, and which is shown in Figs. 1, 2, and 3. In these views, *a* indicates a strong metallic case like a lock-case, and made preferably of steel, cast-iron, or other suitable material not easily tampered with or broken 70 into. This case is shown as in the form of a shallow box or tray closed on the front side and open on the back, and adapted to be covered by a removable plate, if desired. This case is securely set into the front of a hall-door, or door 75 of entrance to the house, with its front exposed flush, or nearly so, with the door, and so secured thereto that it cannot be removed or displaced to gain access to its interior without ready detection. Upon the front of this case two circular recesses, *b*, are formed, in which are socketed two rotary disks, *c c*, which are fixed to central axes, *d d*, which pass through openings in the center of the said recesses, and are connected to rotary disks *e e*, of similar size, 85 on the inside of the case. These inner disks, *e e*, are insulated from the case and from each other, which is best done by making said disks of some non-conducting substance—for instance, of vulcanized or gelatinized fiber—90 while the outer disks, *c c*, and axes *d* are preferably made of strong metal. Upon the inner face of each of the insulating-disks *e e* is fixed a conducting-ring or washer, *f*, of copper or other conducting metal, and each of 95 these washers has a contact tongue or spring, *g*, projecting from the periphery thereof, overhanging the edge of the disk and bearing upon a raised annular seat or contact-strip, *h*, fixed on the inside of the case, around the base of 100 the disks. A contact tongue or brush, *i*, projects from each of the conducting-strips *h* and

bears upon the conducting-face *f* of the opposite disk, as fully shown in Fig. 3. Now, each of the annular contact-strips *h h* has a break therein at one point in its circumference, as shown at *k k* in Fig. 3, which break is a little wider than the overhanging contact-tongues *g* of the disks, so that hence, if the disks are turned so that their tongues will be over the gaps *k k*, they will be out of contact with the strips *h h*. Now, the circuit-wires *lm* connect, one to the first contact-strip *h* and the other to the last contact-strip *h*, and in this circuit *n* indicates the battery, *o* the alarm-bell or other indicating and announcing device, and *p* represents one of the contact-springs on the doors, window, or other protected parts, which is of course shown in its open position. We will now assume that the disks are so turned that their contact-tongues bear on the strips *h h* at any point of their circumference, as shown in Fig. 3, and if while in this position the contact-spring *p* on the door or window is closed the circuit will then be immediately closed, being completed through the contact tongues and strips of the switch, as indicated in Fig. 3, and hence the alarm *o* will be sounded. It will be further noted that the circuit will always be completed through the switch in all positions in which the disks may be turned, except the one particular position in which the tongues *g* register with the gaps *k k*, and if the disks are brought in this position the circuit will be broken. Consequently, if the owner or other entrusted person desires to open any part protected by the circuit without sounding the alarm—for example, if he wishes to enter the house late at night, while the occupants are asleep, without disturbing them—he will simply turn the disks so that the tongues of both are over the gaps *k k*, so that now when he opens the door, and thereby closes the contact-spring *p*, no alarm will be sounded, since the circuit has been previously broken through the switch, and hence he can enter noiselessly, whereas any one not understanding the secret of the switch cannot do so.

It will be noted that where the switch is provided with two disks and their adjuncts both disks must be turned to the break before the circuit will be broken, for, if but one disk is so turned, it will be observed that a passage for the current will yet be afforded through the contacts of the other disk. Thus, referring to Fig. 3, it will be seen that a double passage is afforded for the current, while both disks are turned into their conducting positions—that is, the current may flow from the first ring *h* to the tongue *g* and face *f* of the first disk, thence by the upper brush *i* to the second ring *h*, and thence back to the battery; or it may also flow from the first ring *h* through the lower brush *i* directly to the face *f* of the second disk, and thence through its tongue *g* to the last ring *h*, and thence back to the battery, so that unless both disks are turned so that their tongues *g g* are over the breaks *k k*

the circuit will not be left open when the contact *p* is closed. This duplex arrangement obviously complicates the switch and renders it very difficult for any one not knowing its secret to so turn the disks as to break the circuit, and it also reduces the possibility of the switches being accidentally turned or left by the owner in a position in which the circuit will be broken. If desired, however, but one disk and set of contacts may be used, or, on the other hand, a much greater number of disks and contacts than those shown may be used, every additional disk adding to the complication and consequent safety of the device, as will be understood; but I prefer to use two or three disks only, as that is thought to be quite sufficient for safety. Now, in order to enable the person in the secret of the switch to know from the outside of the case in what position to turn the disks so that they will break the circuit, the range through which the disks are movable is graduated into a number of divisions, and these divisions numbered or otherwise designated, as shown in Fig. 1, in a manner similar to that employed in permutation or combination locks.

I prefer to mark the graduations on the face of the case around the periphery of the disks, as shown, and on the faces of the disks are bored a series of small screw-holes, *r r*, corresponding in number and positions with the said graduations, and into any one of these screw-holes a little changeable screw-pin, *s*, may be screwed tightly, as shown in Figs. 1 and 2, which pin will serve as a handle or crank-pin by which the disk may be readily revolved, and also as an index-point to show to what figures the disks must be turned in order to open the switch, according to the combination to which it may be set. Now, each of the said graduations or divisions is equal in width to the breaks or gaps *k k* in the contact-strips *h h*, as will be readily understood from the dotted lines in Fig. 1, and hence, if the disks are so turned that the tongues *g* of both disks are over the gaps *k k*, the switch will be open, as before described, and the pins *s* on the face of the disk will be opposite some of the figures on the face of the switch. In the present case the pins will be opposite the figure "9" on the first disk and the figure "4" on the second disk; consequently "94" is the combination to which the switch will open; but if the disks are turned to any other set of figures the switch will not be opened; hence the disk can be turned to only one out of a larger number of positions in order to break the circuit, and unless a person knows this combination or number it is obviously useless to attempt to open the switch, and hence the safety and value of the device for electrical circuits are obvious.

Now, in order to change the number or combination to which the switch will open, it will be observed that it is only necessary to change the screw-pins to another set of holes oppo-

site another set of numbers while the disks are held in their "open" positions, and take note of the numbers, which will be the new combination. For instance, referring to Fig. 1, 5 bring the pins to the number "94," as before described, which will bring the tongues *g g* opposite the break *k*, and thus open the switch, as before described. Now, hold the disks in this position and unscrew the pins *s* and 10 insert them in any other set of holes desired. For instance, insert one pin in the hole opposite "2" on the first disk and "8" on the second disk, when the new combination becomes "28," so that when the disks are again turned so 15 that their pins register with those numbers the switch will be opened, but not in any other position. The combination may thus be changed as often as desired, thus adding to the safety of the device.

20 The modification of my invention for closed circuits is shown in Fig. 4, in which the construction is precisely the same as for the open circuit, except that the broken rings *h h* of the latter are dispensed with, and, instead of the 25 contact-tongues *g* of the disks being arranged to break contact and open the circuit only at one point in their revolution, they make contact and close the circuit only at one point in their revolution by riding upon a contact-seat, 30 *k'*, which corresponds in position and function with the gaps *k* in Fig. 3.

In Fig. 4, *t* indicates the closed circuit, which energizes the usual relay, *u*, and keeps the local or alarm circuit *v* open, in the usual manner. In this closed circuit are disposed the closed contact-springs *p'*, which are fixed on the doors or windows which are protected, and it will be seen that if this spring is opened the circuit *t* will be broken and the armature 40 of its relay *u* will retract and close the local circuit *v*, and thus sound the alarm *o*, in the usual manner. A contact brush or spring, *i'*, bears upon the conducting face of each disk, and these tongues are insulated from each 45 other and from the case of the switch, and correspond in purpose with the brushes *i* of the open-circuit switch, as will be readily understood. One pole of the battery of the closed circuit *t* is connected with the brush *i'* of the 50 first disk, and the other pole of the battery is connected with the seat *k'* of the second disk, while the opposite seat, *k'*, and brush *i'* are connected together by a short wire or conductor, *h'*. It will therefore be seen that if 55 the disks are so turned that the tongues *g* of both will seat upon the seats *k'* the circuit *t* will be closed in a shunt around the contact-spring *p'* through the aforesaid parts of the switch, and consequently the door or other part 60 protected by the contact-spring *p'* may now be opened without breaking the circuit, for the reason that the circuit has been previously closed or shunted around the spring through the switch. If, however, the disks are set in 65 any other position except in that named, the circuit will be open through the switch, and

hence the door cannot be opened without sounding an alarm, and this position can be found only by the person knowing the combination to which the switch may be set, which 70 is done in precisely the same way as already described in referring to Figs. 1 and 2, as will be readily understood.

I do not, of course, confine myself to the precise constructions illustrated, as many modifications may be adopted without departing from the principle of the invention shown.

Instead of the changeable pins *s*, with holes *r* and the figures around the socket of the disks, any other equivalent means for indication and permutation may be used, and, instead of making the switch with two or more distinct disks adjoining each other, the switch may be made with parallel sliding switch-plates, or with two or more rotary rings mov- 85 able concentrically within each other, which will form a compact substitute for the separated disks; but I prefer the disks.

Referring to Figs. 3 and 4, it will be noted that the parts *f g* may be called the "conducting body" of the switches and the parts *h or h'* the "seats" of the switches, while the parts *i* or *i'* are brushes or conductors which connect the body of one switch with the seat of the other switch.

As the closed-circuit switch shown in Fig. 4 is a mere modification of the principal form of my invention for open circuits, I consider that the same is covered in the principal claims as an equivalent, although the language of the 100 said claims, for greater clearness, refers more particularly to the open-circuit form of switch.

What I claim is—

1. A secret permutation electrical switch, consisting of one or more commutators or 105 switches movable through a graduated path or range and upon a seat whose continuity is interrupted at a certain point or graduation in said path, and at which point of interruption the circuit is opened, with means, substantially as set forth, for secretly indicating the position or graduation of said point of interruption, and means, substantially as set forth, for changing the indications or graduation representing said points, substantially as herein set 110 forth.

2. An electrical permutation-switch, consisting of two or more contact-makers or switches movable through a graduated range or path and upon a seat the continuity of which is interrupted at a certain point, and at which the circuit is opened, with a contact brush or conductor connecting each switch with the seat of the other switch and with circuit-connections extending to the said seats and brushes, 120 substantially as set forth, whereby a duplex or multiplex passage is afforded for the current through the several contacts of the said connected switches, and whereby the circuit will become opened or closed only when all 125 the contacts are set to their position of break, substantially as herein set forth.

3. A secret permutation-switch for electrical circuits, consisting of two rotary contact-makers or switches, each movable through or over a graduated circle and upon a seat 5 which is interrupted at a certain point to interrupt the circuit, with brushes or conductors connecting each switch with the seat of the other switch and circuit-connections with said seats and brushes, substantially as and for the to purpose set forth.

4. An electric switch substantially such as described, formed with the rotary contact-maker *f g*, in combination with the seat *h* and brush *i*, with circuit-connections extending to

said seat and brush, substantially as herein 15 set forth.

5. An electrical switch substantially such as described, having one or more plates or disks perforated with holes, in combination with changeable crank-pins adapted to be fixed 20 in one of said holes, and with graduations corresponding with said holes, substantially as and for the purpose set forth.

CHARLES S. SHIVLER.
